HANDLE FOR INSTRUMENTS FOR MAKING EXAMINATIONS

Original Filed Sept. 4, 1924

Inventor:
WILL J. CAMERON
E. J. Lundell Atty.

UNITED STATES PATENT OFFICE

WILL J. CAMERON, OF CHICAGO, ILLINOIS

HANDLE FOR INSTRUMENTS FOR MAKING EXAMINATIONS

Application filed September 4, 1924, Serial No. 735,973. Renewed February 6, 1928.

My present invention relates to a handle for instruments used in making surgical, dental or optical examinations, inspections and diagnoses. More particularly my present invention has reference to a handle that may be removably secured to an ophthalmoscope, retinoscope or other optical instrument, or to a speculum or similar surgical instrument, so that the operator may readily examine tissues remote from external observation. The construction of this handle is such that the tissue under investigation will be illuminated by the rays of a miniature bulb or lamp which rays are magnified through a lenticular element in the end of the handle and with which the rays may be focused upon the part under inspection.

The primary object of my invention resides in the provision of a handle wherein is carried the miniature bulb or lamp in a socket element and which is adapted to be rotated upon its axis and may be bodily moved longitudinally by means of a control element that is operable from the exterior of the handle. Another object of my invention resides in providing a handle structure that may be readily attached to or detached from the surgical or optical instrument and which effectively coacts therewith so as to illuminate the area under observation. In ophthalmoscopes, it is desirable to provide an illumination, especially when inspecting the retina of the eye, which is in the form of a narrow line or transversely condensed beam or ribbon of light. With my improved handle I am able to rotate the bulb or lamp until the incandescent filament therein is so disposed with relation to the magnifying lens and the projecting reflector of an ophthalmoscope, and I am also able to move the bulb longitudinally toward and away from the lens, until the desired character of illumination is obtained. Further objects of my invention reside in providing a structure of the above character that is extremely compact in the construction and arrangement of its parts; which is dependable in operation; has a wide range of adjustability; and is novel and sturdy in construction.

I prefer to carry out my invention and to

accomplish the aforesaid objects in substantially the manner hereinafter more fully described and as more particularly pointed out in the claims.

Reference will now be made to the accompanying drawings that form a part of this specification, in which

Figure 1 is a vertical side elevation of an optical instrument and my improved handle showing the latter about to be inserted in the former.

Fig. 2 is a rear view of the structure illustrated in Figure 1 but in assembled form and having a portion of the handle and ophthalmoscope socket in longitudinal section.

Fig. 3 is a longitudinal axial section of a fragmentary portion of my improved handle drawn slightly enlarged.

Fig. 4 is an enlarged transverse section taken on line 4-4 of Figure 1, looking in the direction of the arrows.

Fig. 5 is a section on line 5-5 of Figure 3.

Fig. 6 is a fragmentary longitudinal section showing the frictional means in conjunction with the adjusting slide.

In the drawings I have employed the same reference characters to designate like parts wherever they occur throughout the several views, and by referring to Figures 1 and 2 it will be seen my invention comprises a handle that may be removably assembled with an instrument for making surgical, dental or optical examinations, and in the present instance I have illustrated the structure in connection with an optical instrument of the retinoscope type for the purpose of simplicity. The retinoscope, however, forms no portion of my present invention, except insofar as it combines with the idea or invention of the provision of the relative adjustability of the lamp and the lens with respect to each other in a plurality of different directions to control and position the beam of light of ribbon formation with respect to the object upon which it is directed, as retinoscopes generally are understood to embody a head having a sight opening, a light source, and an inclined mirror or reflector interposed between the light and the object. It is designated

by the structure indicated by the numeral 10 which illustrates a retinoscope head and has upon the rear face of its supporting plate an elongated tubular element or socket 11, the upper end of which latter is closed by a lenticular element 12 in axial alinement with an angularly disposed reflector element or mirror 13. The rays in the form of a ribbon of light from a lamp below and alining with the mirror provide a beam of incidence between the bulb and the mirror, and the rays reflected from the mirror provide a beam of reflection, the axis of the respected beams being disposed at an angle to each other. Whenever the beam of incidence is rotated upon its axis the beam of reflection is correspondingly rotated upon the axis. In order to permit inspection of the area illuminated by the ribbon of light the usual retinoscope or ophthalmoscope sight or sight aperture 13^a is provided in the mirror so that it is coincident with or in axial alinement with the light beams or at least with the beam of reflection in order that the latter beam may be viewed through the mirror. The retinoscope head 10 is provided with a viewing or sight aperture 10^a in axial alinement with the beam of reflection and the mirror aperture 13^a. The lower end of the socket 11 is provided with a slit 14 extending longitudinally inwardly from the edge thereof so as to permit of a slight spring action when the end of the handle member is inserted in said socket.

The handle preferably comprises a barrel 15 of tubular form in cross-section, that is preferably elongated, as shown in the drawings, and the upper portion of which is slightly reduced in diameter to provide an annular shoulder 16 against which the lower edge of the socket 11 abuts when the handle is inserted therein. This barrel is formed of hard rubber, bakelite or similar insulating substance. The bore at the reduced end of the barrel is also slightly reduced as at 17 to provide a bearing in which a hollow metal stem 18 is mounted to slide longitudinally therein, and the outer end of the same, which projects outside the barrel 15, is provided with an enlargement or head 19 that is of less diameter than the interior diameter of the socket element 11 of the instrument so that it will not interfere or contact therewith. This head or enlargement 19 is hollow and is internally threaded to provide an electrical socket connector into which is screwed a miniature lamp or bulb 20 of any well known or suitable type having a single filament to project a beam in the form of a narrow line, or a transversely condensed beam or ribbon of light. The opposite end of the hollow stem 18 is exteriorly threaded and has screwed thereon a block 21 of insulating material. The insulating block 21 is provided with a central aperture or bore 22, and a longitudinal groove or channel 23 is formed upon the edge of said block so that

the ends of the electrical conductors 24 may be positioned in the respective aperture and groove, one of which (that lying in the groove 23) being soldered or otherwise secured to the adjacent end of the metal stem 18, while the other (that passing through the central aperture or bore 22) extends through the stem and is connected to the terminal in the base of the electric socket in which the lamp or bulb 20 is positioned. The conductors extend downwardly to the opposite end of the barrel 15 where their ends are connected to terminals or posts 25 that are spaced apart parallel with each other and pass through an insulating block 26 in the adjacent end portion of the barrel 15, and said terminals or posts 25 are of sufficient length to project beyond the end of the barrel, as seen in Figures 1, 2 and 3 of the drawings, so that when the electrical connection is made 85 the miniature plug having cylindrical terminals may be inserted into the end of the barrel with the terminals telescoping the posts or pins 25 in the well-known and usual manner.

The barrel adjacent the inner end of the spindle 18 is provided with a lateral aperture 27 that is preferably of the desired height and width to permit of the engagement of the spindle by means of an exterior element that is connected therewith so that 95 said spindle may be rotated and moved longitudinally whenever desired. Surrounding and at all times closing the aperture 27 is an elongated sleeve or slide 28 that frictionally engages the outer surface of the barrel 15 and which is connected to the spindle 18 by means of a screw 29 that passes through said sleeve and is screwed into a tapped opening in the insulating block 21 at the adjacent lower end of the spindle. In this means the sleeve 28 100 may be slid longitudinally upon the barrel and in any position or any time it may also be rotated and the spindle 18 carrying the lamp or illuminating element 20 will be correspondingly moved so that a wide range of adjustment is possible within the limits of the aperture 27 in the barrel. In using the instrument, the retinoscope is held before the patient in the usual manner so that the flat beam or ribbon of light from the lamp will pass through the lens to the mirror 13 from which it is reflected into the eye to be examined, the operator making his observation through the sight 10^a and 13^a in the usual way. Thus it will be seen that the projected beam or ribbon of light may be applied to any selected meridian of the eye and by turning the sleeve 28 the beam or ribbon of light may be placed at right angle to the meridian selected. It will be obvious that in turning the lamp the center of the beam or ribbon of light will always remain coincident with the center or axis of its rotation so that the ends or extremities or ribbon will describe the circumference of an imaginary circle. This renders it unnecessary 120 125 130

to rotate the beam or ribbon of light more than one hundred and eighty degrees in order to examine any desired meridian by turning the beam or ribbon of light at right angle thereto, the transverse or circumferential extent of the slot 27 being merely sufficient to permit the sleeve 28 to be turned half way around or one hundred and eighty degrees. When the sleeve 28 is moved longitudinally of the handle the transverse dimensions of the beam or ribbon of light is varied, since by such movement the distance between the lamp filament and the lens is varied. The slot 27 determines both the longitudinal and the rotary movement of the lamp filament, and this slot is so proportioned that when the operating sleeve is at the upper end of its movement the rays passing through the lens will be divergent and produce a plano mirror effect. When the sleeve is moved in the opposite direction or downwardly the rays become convergent and focus along a line so that the ribbon of light becomes transversely condensed and narrowed. The longitudinal extent of the slot 27 is such that the lamp may be moved away from the lens sufficiently to produce the effect of a concave mirror retinoscope. In order to provide additional friction between the barrel and the sleeve 28 I have formed a shallow groove 30 in the outer surface of the barrel 15 in which is positioned an outwardly bowed spring element 31 that bears against the interior surface of the sleeve 28 and creates sufficient friction to maintain the parts in their divers adjusted positions.

From the foregoing it will be seen that the tubular element of the examination instrument may be mounted upon the handle, and, when the slide 28 is moved longitudinally upon the barrel, the lamp or bulb will be moved longitudinally within the tubular element 11 so as to adjust the filament of the lamp with respect to the lenticular closure 12 and this adjustment may be both longitudinally toward and away from the lens or in a rotary direction so that the filament of the bulb will be properly positioned to direct a flat beam of light through the lens which will direct it toward the reflecting mirror 13 and from thence upon the tissue under inspection. The handle element is readily removable from the instrument, and the same is capable of use upon several instruments of different types and in the case of a speculum the lamp may be slightly withdrawn below the line of vision through the structure and will not interfere with the observation of the parts under inspection or hinder the use of instruments that may be inserted through the speculum.

What I claim is:—

1. In a handle of the class described, a tubular body having a wide elongated opening in one side, an extension having a bore of less diameter than the bore of said body,

a stem slidably and rotatably mounted in the bore of said extension and projecting above and below said extension, an enlarged head at each end of said stem to provide limiting stops therefor, a sleeve surrounding the body at the opening and connected to the inner head through said opening for rotating and reciprocating said stem, a lamp carried by the outer head, and yieldable friction means interposed between said sleeve and body for maintaining the former in its divers positions of adjustment. 70

2. A device of the kind described comprising a tubular body having an elongated opening in one side, an extension having a bore of less diameter than the bore of said body, a stem movable in the bore of said extension and projecting above and below said extension, enlarged heads at the ends of said stem to provide limiting stops therefor, a slide movable upon the exterior of the body at the opening and connected to the inner head through said opening for moving said stem in a plurality of directions, a lamp carried by the outer head, and a tubular element assembled with said extension adjacent the lamp, the arrangement of the parts being such that the lamp may be rotated and moved up and down within said tubular element. 85

Signed at Chicago, county of Cook and State of Illinois. 95
